UNITED STATES PATENT OFFICE

2,094,635

INSULATING WALL CONSTRUCTION

John H. Brooks, Cleveland Heights, Ohio, assignor to Ludowici-Celadon Company, Chicago, Ill., a corporation of Illinois

Application April 30, 1937, Serial No. 139,979

2 Claims. (Cl. 20—4)

This invention pertains to building constructions and more particularly to such walls thereof as it may be desirable to heat insulate. While the forms of the invention here illustrated as exemplifying the principles thereof are shown as embodied in the upright walls of a building structure, it should be understood that the principles of the invention are equally applicable to ceilings, roofs, partition walls, and in fact all walls of a building where insulation may be desirable.

The insulation of walls by the employment of either loose insulating material or insulating material formed into bats or packages is common practice; but heretofore, so far as I am aware, the insulating bats when employed have been either of a depth equal to the depth of the studs or joists between which they are positioned, thereby forming a substantially solid wall without provision for air space, or, when made of less depth than the depth of the joists or studs, have been equipped with flanges projecting from the bodies of the bats and adapted to be attached by nails or otherwise to the studs or joists to thereby hold the bats in position. These latter bats, thinner than the depth of the joists, possess the advantage that less insulating material is required in their production, but this cost is substantially offset by the cost of providing them with the flanges or projections for securing them in place.

My present invention in its preferred form contemplates the employment of a bat containing less insulating material than is required for a full depth bat, thereby decreasing the cost of manufacture and also enabling the provision of an air space in the wall structure for insulation and anti-humidity purposes. Furthermore, it eliminates the expensive flanges or projections heretofore formed on the bats for fastening purposes, thereby reducing the cost of the construction without impairing its insulating functions.

Another feature of my invention resides in the provision of fastening means for the bats which are so constructed that they will overlie the joints between contiguous bats, thereby enabling each fastening device to hold in place the adjacent portions of two adjoining bats, that is, each fastening device will hold the upper end of one bat and the lower end of a superposed bat.

Another desirable feature of my invention is that the preferred forms of my improved fastening devices serve not only to hold the bats in position but also cover and seal the joints between adjacent bats, thereby increasing the insulating properties of the wall structure.

For the purpose of exemplifying the principles of my invention, I have illustrated on the accompanying drawing preferred embodiments thereof.

Referring to the drawing,

Fig. 1 is a fragmentary perspective view of a wall construction built in accordance with my invention;

Fig. 2 is a sectional view thereof on the line 2—2 of Fig. 1;

Fig. 3 is a view similar to Fig. 1 illustrating a modified form of bat holding or fastening device; and

Fig. 4 is a similar view illustrating the embodiment of still another form of fastening device.

Referring to the drawing more in detail and particularly to Figs. 1 and 2 thereof, reference character 5 indicates generally the supporting sill or plate upon which the wall structure is carried. The studs 6, or the rafters if the invention be embodied in a roof, are arranged in usual spaced relation along the plate 5 and to the outer faces of these studs is secured, by nailing or otherwise, the sheathing 7 which forms the base for the outer covering, not shown, of stucco, shingles, brick, veneer, or the like. The floor joists 8 may be supported at their ends upon the plate 5 and carry the floor boards 9.

The skeleton wall structure is rendered heat insulating by positioning in the spaces between the studs 6 bats 11 of heat insulating material, such as rock wool, asbestos, vegetable fiber, or other suitable material, formed preferably under slight pressure into rectangular blocks or packages, paper being ordinarily employed as a wrapping for the material to retain it in units for convenient shipping and handling. These bats, in accordance with my invention, are superposed one upon the other in the spaces between the studs and against the inner face of the sheathing 7. It will be observed that the bats are of less thickness than the depth of the studs 6 so that when positioned as illustrated the inner faces of the bats are spaced outwardly from the inner edges of the studs.

To hold the bats in this position against the sheathing, my invention contemplates the employment of fastening devices designated generally by reference character 12, each of which consists of a strip or plate of suitable material provided at each end with an inturned flange 13 adapted to lie against the side of the stud 6 to which it is secured by one or more nails or staples 14, as shown. The fastening devices may be made of paper (either plain or corrugated), fiber board composition, sheet metal (either plain

or reticulated), or any other material that may be available possessing the requisite strength and rigidity. These fasteners, as will be evident from the drawing, are positioned to cover the joints between superposed insulating bats, so that each device holds in position the upper end of one bat and the lower end of the next superposed bat. Each fastening device, therefore, not only functions to hold the adjacent ends of two bats in position but also covers and substantially seals the joint between the bats, thereby increasing the insulating properties of the wall structure.

The inner faces of the studs carry any suitable wall surfacing material 15 which may be in some instances lath and plaster or in other instances wall board either plastered or unplastered; but, in any event, a dead air space between this wall surfacing material and the inner faces 20 of the bats is provided between the spaced studs, which serves not only as an insulation in addition to the insulating bats but also is adapted to some extent to take up moisture which may inadvertently enter the wall.

25 In the modification of the invention illustrated in Fig. 3 the fastening devices 16, which preferably are in the form of metal clips or bars, do not extend from stud to stud as do the fastening devices 12, and, instead of being secured or 30 anchored to the studs, they are secured or anchored to the sheathing 7 by long nails or spikes 17 which extend through the joint between adjacent bats and into the sheathing. In this instance, the fastening devices, like the devices 12, serve to hold in place the upper and lower ends of superposed bats but do not serve to cover and seal the joints between the bats, except to a limited extent.

In the modification illustrated in Fig. 4 the 40 bats 18 are of the same thickness as the depth of the studs 6, with the result that no dead air space is left in the wall structure. The fastening devices in this instance are designed not only to hold the bats in position but to effectually seal 45 the joints between the bats and, therefore, consist of strips 19 of strong paper or other fibrous material preferably provided on the outer face thereof with a suitable gum or adhesive which when moistened will adhere to the studs and to 50 the bats, thus effectually sealing the joints between superposed bats. As an additional assurance against loosening of the fastening strips from the studs, nails or staples 21 may also be

employed, if desired, and, as illustrated, an intermediate fastening strip may be placed between the joint sealing strips as supplemental holding devices for the bats.

It will be apparent from the foregoing that I 5 have provided a wall construction which, in the preferred embodiment shown in Fig. 1, utilizes insulating bats considerably thinner than the standard bats, and that provision for a dead air space as an insulating medium in conjunction 10 with the thinner bats is made. Furthermore, the fastening devices, which can be very economically produced, serve to hold the bats in position against the sheathing and also serve to seal the joints between the bats, each fastening device 15 being adapted to hold the upper end of one bat and the lower end of a superposed bat.

In the form shown in Fig. 3 the sealing of the joints between the bats is sacrificed in favor of the cheaper fastening clips 16.

In the form shown in Fig. 4 the joints between the bats are not only covered by the fastening devices but are completely sealed by the strip form fastening devices which are secured to the margins of the bats adjacent the joints by 25 adhesive.

It is believed that my invention and many of its inherent advantages will be appreciated from the foregoing without further description, and it should be manifest that deviations from the 30 structural details shown for illustration purposes may be made without departing from the spirit of the invention as defined in the following claims.

I claim:

1. An insulating wall construction comprising studs disposed in spaced relation, sheathing carried by said studs, insulating bats positioned between the studs, and fastening means for holding said bats in position against the sheathing, 40 said means being secured at their ends to the studs in position to overlie the joints between adjacent bats and engage the bats at opposite sides of said joints to thereby hold the bats in position and cover the joints between adjacent 45 bats.

2. A wall construction comprising spaced studs, superposed bats arranged between adjacent studs, and relatively narrow elongated fastening devices sealing the joints between the superposed 50 bats and secured to the studs for holding said bats in position.

JOHN H. BROOKS.
